RECEPTACLE FOR GARBAGE CANS

John Vernon Kyle, Atlanta, Ga., assignor to
Atlanta Concrete Pipe Company, Atlanta, Ga.

Application August 15, 1939, Serial No. 290,332

2 Claims. (Cl. 72—13)

The present invention relates to new and improved receptacles for garbage cans.

An important object of the invention resides in the provision of a receptacle of the type above-identified that is formed of concrete or similar material, the major portion of which is submerged in the ground providing a maximum of cleanliness in the disposition of garbage.

A further object of the invention is to provide a receptacle for the garbage can which will fully protect the same from the weather thereby improving its efficiency from a sanitary standpoint. The garbage can is removably disposed within the embedded receptacle and covered by means of a closure member forming a part of the receptacle permitting periodic emptying of the garbage can and at the same time maintaining the same in a concealed manner.

The invention will be fully and comprehensively understood from a consideration of the following detailed description when read in connection with the accompanying drawing which forms a part of the application.

In the drawing:

Figure 1 is a perspective view of the receptacle with the cover being shown in raised position.

Figure 2 is a vertical sectional view of the same, and

Figure 3 is a top plan view thereof.

In the embodiment of the invention as disclosed in the drawing, there is provided a receptacle formed of concrete or similar material embedded within the ground and adapted to receive a garbage can. The receptacle is provided with a cover hinged thereto and adapted to be foot operated for raising the same whereby the garbage can be readily positioned and removed from the receptacle.

Referring to the drawing for a more detailed description thereof, the receptacle generally designated by the reference numeral 5 has its major portion placed beneath the ground as clearly indicated in Figures 1 and 2. The receptacle 5 is preferably cylindrical in form having side walls 6 formed of concrete and with each end thereof opened. The cylinder 5 is preferably formed in a mold of a desired size and before placement beneath the ground, a relatively heavy base 7 of crushed gravel or the like is placed at the bottom of the opening, the same being slightly smaller than the inside diameter of the receptacle 5 whereby said receptacle may be disposed thereon in the manner shown in Figure 2. The base 7 forms a support for the 55

garbage can to be contained within the receptacle.

The upper end portion of the receptacle extends above the ground, which end is reduced 5 and has an upwardly and inwardly inclined outer surface 8 forming a shoulder 9 upon which the hinged cover 10 rests. The reduced upper end of the cylinder is reinforced by one or a plurality of steel wires 11 embedded therein, the same being reinforced to alleviate the possibility of damage thereto upon frequent opening and closing of the cover 10.

The cover 10 is preferably formed of a relatively heavy gauge metal, said cover completely enclosing the upper reduced end of the receptacle and resting upon the shoulder 9, as more clearly shown in Figure 2 of the drawing. A hinge generally designated at 12 is provided for securing the cover to the receptacle, said hinge comprising the member 13 secured by means 14 to the cover and a second member 15 bolted or otherwise secured as indicated at 16 to the outer surface of the wall 6. The members 13 and 15 are united by means of a pin 17 whereby the member 13 is adapted to swing on the member 15. The member 13 secured to the cover 10 is provided with an angular foot piece 18 through the medium of which the cover may be conveniently raised and said hinge member is also provided with a stop 19 adapted to engage the other hinge member 15 for limiting the opening movement of the cover.

As is to be understood, the garbage can to be used within the receptacle is to be provided with 35 a bail for convenient placement and removal of the same and the can to be of a size to be readily positioned and removed therefrom. With the can disposed within the receptacle and the cover member 10 in closed position, said can will be 40 completely protected from the weather as well as preventing the escape of foul odors therefrom and otherwise improving the sanitary efficiency of the receptacle.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the

invention nor exceed the scope thereof as expressed in the appended claims.

What is claimed is:

1. In a receptacle for garbage cans, a cylindrical container forming body fitted within a cavity in the ground so that its bottom open end is disposed on the bottom of the cavity and having a fractional portion of its length projecting above the ground to provide a protruding upper portion, the top end of the container being externally reduced to form a horizontal relatively narrow shoulder merging into a frusto-conical section having a reduced taper toward the top edge, and a round cover section hingedly connected with the protruding upper portion of the container, the said cover section formed of sheet metal having its marginal portion shaped to form a frusto-conical rim adapted to fit snugly on the frusto-conical portion of the container top and having a laterally projecting flange adapted to fit snugly upon the shoulder of the container.

2. In a receptacle for garbage cans and the like, a cylindrical container having its major por-

tion fitted within a cavity in the ground with its bottom end portion tightly fitted over the upper portion of a circular block of solid material disposed in the bottom of the cavity, the said container having the minor portion of its length projecting above the ground to form a protruding upper part, the top portion of the said container being reduced externally and shaped to form a horizontal shoulder substantially above the ground and a frusto-conical neck portion having a reduced taper from the shoulder to the top edge of the container, an annular reinforcing member embedded in the top reduced portion of the container, a cover fitted to close the raised top end of the container, an annular marginal portion formed on the cover having a frusto-conical section adapted to fit snugly upon the frusto-conical neck portion of the container and having an outwardly directed flange formed at its periphery adapted to seat tightly on the shoulder of the container, and a hinge for pivotally connecting the cover with the protruding upper part of the container.

JOHN V. KYLE.
